UNITED STATES PATENT OFFICE.

WILLIAM C. AVEDON, OF NEW YORK, N. Y.

CLOSURE FOR GARMENTS AND OTHER PURPOSES.

Application filed March 20, 1923. Serial No. 626,446.

REISSUED

To all whom it may concern:

Be it known that I, WILLIAM C. AVEDON, a citizen of the United States, residing at 838 Riverside Drive, New York city, in the 5 county of New York and State of New York, have invented certain new and useful Improvements in Closures for Garments and Other Purposes, of which the following is a specification.

10 My invention relates to a new and improved closure for garments and other purposes.

One of the objects of my invention is to provide a new and improved closure which 15 shall be an improvement upon the type shown in the Sundback Patent 1,219,881, issued on March 20th, 1917, for a separable fastener, although my invention is not limited to use with fastening means of the particular type shown in said patent, as fastening means having the same general function have been heretofore known and described.

Another object of my invention is to provide a new and improved fastening means 25 whereby the two pieces of cloth or other material which are connected by the fastening means can be completely separated at one end thereof and can then be readily refastened to each other.

30 Another object of my invention is to provide a new and improved fastening means whereby the movement of a control member in one direction will automatically open the said fastening means at one end thereof and 35 whereby the movement of the said control member in the opposite direction can prevent the separation of the said fastening means.

Other objects of my invention will be set 40 forth in the following description and drawings which illustrate a preferred embodiment thereof.

In the drawings I have only conventionally illustrated the accessory details which 45 may be of the type shown in the before mentioned United States Patent 1,219,881, as my invention is not particularly directed to or limited to any such special type of fastening members.

50 Fig. 1 is an elevation.

Fig. 2 is a top view of the guide member.

Fig. 3 is a section along the line 3—3.

Fig. 4 is a section on the line 4—4 of Fig. 2.

55 Fig. 5 is a side elevation of Fig. 2.

As shown in Fig. 1 my fastening means

are adapted to completely close two strips A and B which may be made of fabric or any other suitable material. These two strips may constitute the means for opening 60 and closing any suitable garment, such as brassières, corsets and the like.

The bottoms of said strips A and B may be permanently joined as desired or these strips A and B may be completely separate 65 throughout their entire lengths which may correspond to the entire length of the garment, if this invention is applied to a garment, such as a brassière.

The strips A and B are provided with 70 fastening members F which may be of the type shown in the said United States Patent No. 1,219,881. The control member 7 consists of upper and lower lips, such as shown in the said United States Patent No. 75 1,219,881 and these upper and lower lips each have a Y shape and they have a wedge-shaped tongue 9 between them so that the movement of the said guide member 7 in one direction causes the fastening means F to 80 automatically interlock or to be automatically separated, as shown in said United States Patent No. 1,219,881. The combination of members F and guide member 7 is 85 well known. However, such closures have been used in combination with fabric strips permanently connected to each other at both ends thereof. Hence, this type of closure cannot be used in garments such as brassières in which the garment is put on and 90 taken off like a coat.

The strips A and B may be provided at their adjacent ends with metallic end closure members 1 and 2. The closure member 1 has a shoulder 4 provided with a tongue or 95 dog 3. The said member 1 constitutes what may be called the entering member since it enters into and interlocks with the entered member 2. The entered member 2 has a recess corresponding to the shape of the dog 100 provided on the entering member 1 and this recess has a notch or recess 6 into which the point of dog 3 may enter.

Hence, the wearer can manually interlock the members 1 and 2 when the projection 3 105 fits into the recess 6 and the members 1 and 2 are therefore closely interlocked and by then moving the guide member 7 downwardly so as to interlock all the fastening members F it is impossible to separate the 110 strips A and B.

If, however, the guide member 7 is moved

upwardly, this automatically separates all the fastening members F including those directly adjacent the members 1 and 2 and the further movement of the guide member 7 5 causes the tongue 9 to pass between the bottoms of the fastening members 1 and 2 so that the fastening member 1 is rocked away from the member 2 as the slot 6 is made sufficiently wide to allow for a certain rock- 10 ing movement. The tongue 9 therefore presses against the member 1 until it is completely removed from the entered member 2. The parts are thus completely unlocked and the member 2 is provided with a head H to 15 prevent the removal of the guide member 7.

When it is desired to relock the strips A and B, the wearer manually interlocks the members 1 and 2 and by fastening together the adjacent members F any rocking move- 20 ment of the member 1 is prevented and hence it cannot be accidentally unlocked from the member 2. The slide or guide member 7 has a band 8 connected thereto, to which a piece of ribbon can be connected for manipulat- 25 ing slide 7. When the members 1 and 2 are connected, their inner ends are separated so that the thin end of wedge-shaped tongue 9 can enter between them and separate them.

I have described a preferred embodiment 30 of my invention but it is clear that numerous changes and omissions can be made without departing from its spirit.

It will be observed from Fig. 1 that the length of the projection 3 is slightly less 35 than the width of the recess 6 which may be called the longitudinal recess, although its axis is somewhat inclined to the strips A and B. Hence when the fastening members F adjacent the members 1 and 2 are forced 40 apart by the upward movement of the slide

7, the member 1 is rocked to such an extent that the wedge 9 can pass between the members 1 and 2 and completely separate the said members 1 and 2.

The slide 7 has a projection 8 to which a 45 manipulating member can be connected.

The wedge member 9 preferably has arcuate sides.

I claim:

1. An end closure for two strips having 50 interlocking fasteners adapted to be connected and separated by the movement of a slide member adapted to be slid to and fro over said interlocking fasteners, comprising an end entering member secured to 55 one strip, and an end entered member secured to the other strip, said end members being adapted to interlock and to be manually engaged and disengaged, said end members being adapted to move their adjacent 60 fasteners into proper position to be connected by said slide member when they are interlocked.

2. A device according to claim 1 in which the entered end member has a lateral recess 65 and a longitudinal recess communicating with said lateral recess, and the entering member has a lateral shoulder adapted to enter said lateral recess, said lateral shoulder having a longitudinal dog adapted to 70 enter said longitudinal recess, the said longitudinal recess being of greater diameter than said dog.

3. A device according to claim 1 in which the inner ends of said end members are separated when they are interlocked.

In testimony whereof I hereunto affix my signature.

WILLIAM C. AVEDON.
